NAP-RAISING, SLEEKING, AND THE LIKE
FABRIC DRESSING MACHINE

August Schiffers, Aachen, Germany

Application August 5, 1932, Serial No. 627,653
In Germany August 12, 1931

11 Claims. (Cl. 26—33)

This invention relates to nap-raising, sleeking and the like dressing machines for textile fabrics and has, more particularly, reference to machines of these types in which the working cylinders, such as the raising, sleeking or brushing cylinders are provided with teasel-rolls or card-laths, roller teasels or card rollers and the fabric is conveyed by means of tension and guide rollers through the machine in such a manner 10 as to make contact with the respective working cylinders at a plurality of successive sections.

The working cylinders of these machines have a rather irregular circumferential surface due to the fact that it is impossible to arrange the teasels 15 or cards so that the tips of their bristles or wires have all the same radial distance from the central axis of the cylinders. In result thereof, the raising or sleeking effect on the fabric is also irregular and at the points where the engagement 20 of the teasels or cards with the fabric becomes too strong, the teasels or cards will be quickly clogged with fibres and the like.

It is one of the objects of the present invention to overcome the said drawbacks, this being attained by mounting all tension rollers and, if desired, the guide rollers also in a yieldable manner so that the tension rollers can accommodate 25 themselves to the irregularities of the surface of the working cylinders and the engagement between the fabric and the cylinders becomes a soft one. As a further result of this yieldable mounting, the fabric at the places of contact with the cylinders will bear on the same uniformly and the raising or sleeking effect is considerably 30 ameliorated.

Another object of the invention resides in making provision for the tension of the fabric to remain unchanged when the tension and guide rollers are displaced relatively to the working cylinders for bringing the fabric into or out of operative contact with the cylinders. To this end, the supporting and adjusting means for the tension and guide rollers are so constructed that when operated they impart to the tension rollers 45 a stroke of movement different from that of the guide rollers. It is thereby attained that in re-engaging the fabric with the cylinder surfaces the fabric will apply thereto perfectly stretched, that is to say without the formation of any folds 50 which might entail an unequal dressing effect or even a napping through of the fabric at the folds. The adjustment of the tension rollers and guide rollers is effected interdependently and through one and the same operating mechanism.

55 With machines constructed according to the in-

vention, the surface of the teasels and cards is utilized as much as possible, since the arcs of contact between the fabric and the cylinder surfaces can be chosen comparatively large and arranged in close succession to each other around the circumference of the cylinders, so that a great number of contacts can be made on the cylinders.

Still another object of the invention consists in providing means for positively driving all or some of the guide rollers so that they will aid in the feed of the fabric around the cylinders. In the known machines the fabric feeding was generally performed only by a positively driven feed roller arranged at the inlet and outlet for the fabric, but this was unsatisfactory because the fabric in passing round the cylinders was subjected to excessive strain and therefore lengthened. In a machine in which the said guide rollers are also positively driven, any deleterious strain in the longitudinal direction of the fabric and lengthening thereof are avoided.

Apart from the above general improvements to nap-raising, sleeking and the like dressing machines contemplated in accordance with the invention, the invention still further consists in some novel arrangements in connection with wet sleeking machines comprising a sleeking cylinder, a brushing cylinder and a felting cylinder.

In the known machines of this kind, it is not possible to watch the treated side of the fabric from outside. Therefore, it is very difficult and cumbersome to ascertain when and whether or not the treatment of the fabric has reached the desired degree of finish. It is also difficult for the operators to gain access to the teasel-rods for removing or turning the same, since in these machines the vat for receiving the goods being treated is arranged in front of the sleeking cylinder at one side of the machine and the goods are conveyed to the cylinder from the vat at this particular side. Thus the vat and the machinery parts above the same greatly impede the access to the sleeking cylinder from the front side, the rear side being entirely inaccessible because the goods pass around the cylinder at that side.

These evils are overcome according to the invention by arranging the vat underneath the sleeking cylinder and feeding the goods from the vat to the sleeking cylinder at the outer or rear side of the machine leaving a portion of the cylinder open at that side for gaining free access to the teasel rods. Besides, the guiding means for the goods are arranged so that the goods in passing from the sleeking cylinder, which is mounted in the lower portion of the machine, to

the brushing and felting cylinders, which are mounted in the upper portion, and from the felting cylinder down again to the vat or to conventional winding rollers have their treated side 5 turned outwardly so that it can be readily inspected from the outside. The arrangement of the vat underneath the main cylinder also allows of making the vat of large dimensions and capacity and of catching any water emerging from 10 the wet goods by the vat, while formerly such water was thrown out of the machine.

A further essential feature of the sleeking machine according to the invention consists in that 15 all rotating elements, such as the working cylinders and rolls, clearer rolls, roller temples, feed rollers and winding rollers are positively driven from one common motor carried by the frame through the intermediary of cased spur wheel, bevel wheel and sprocket wheel gearings. Thus, 20 there are avoided belt drives which, owing to their liability to slip, often produce irregular movements of the driven elements and of the fabric itself with the result that the fabric slackens or is excessively strained, thereby entailing 25 non-uniform dressing of the fabric. With the positive drive according to the invention, a uniformly dressed product is attained and accidents are prevented.

The invention is illustrated by way of example in the accompanying drawings.

In these drawings:

Fig. 1 is a longitudinal section of a sleeking machine constructed according to the invention, the central portion being omitted. Fig. 2^a is 35 a transverse section of one portion and Fig. 2^b a similar section of the complementary portion of the machine. Fig. 3 is a side elevation of the machine. Fig. 4 is a diagrammatical view illustrating the guiding of the fabric around the 40 main or sleeking cylinder. Fig. 5 is a detail view of the carrying and adjusting device for the fabric tension and guide rollers. Fig. 6 is a view similar to Fig. 4, illustrating a positive drive for the guide rollers. Fig. 7 is a detail view of 45 the gearing for positively driving the rotating elements of the machine.

Referring to the several figures, and more particularly to Figs. 1-3, F designates the fabric under treatment, 10 is the framework of the sleeking machine, 11 is the main or sleeking cylinder with the teasel-rods or the like 11', 12 are the tension rollers and 13 the guide rollers for conveying the fabric around the cylinder 11, 14 is a brushing cylinder, 15 a felting cylinder, 16 a clearer roller for cleaning the brushing cylinder 14, and 17 is a brushing roller for the unfinished side of the fabric. The felting cylinder 15 and the brushing roller 17 are adjustable so as to allow them to be swung into or out of engagement with the fabric. So is also the clearer roller 16 for putting it into or out of engagement with the brushing cylinder 14. Arranged parallelly of the main cylinder 11 at the outer or rear side of the machine is a roller temple 18 designed 55 to feed the fabric F to the main cylinder. Arranged at a certain distance above the temple 18 is a conveying roller 19 over which the fabric passes as it leaves the cylinder 11. As may be seen from Fig. 2^b, a free space x is left above the 60 temple 18 through which access may be had to the main cylinder 11. 18' is a roller temple designed to feed the fabric to the brushing cylinder 14. Associated with the brushing cylinder are tension rollers 20 and guide rollers 21 by which the 65 fabric is held in contact with and conveyed 70 75

around the cylinder 14. The fabric after leaving the brushing cylinder 14 is guided by means of rollers 22 and 23 past the felting cylinder 15. 24 is a feed roller, and 25, 26 are winding rollers or feed rollers, as the case may be, for conveying the fabric back to the vat 27, from which it started to the main cylinder. As shown, the vat 27 is arranged to extend underneath the main cylinder 11. As clearly shown in Figs. 2^a, 2^b, the arrangement of the several feed and guide rollers is so that the fabric, in passing from the main cylinder 11 to the brushing cylinder 14 and from the latter over the felting cylinder 15 to the winding rollers 25, 26 or the vat 27, has its right or treated side directed outwardly so that it can be easily watched and its degree of finish ascertained.

Mounted in each of the side walls of the frame 10 opposite the heads of the main cylinder 11 and concentrically with the axis of this cylinder is a bevel gear 28 surrounded by a cylindrical casting 29, see Figs. 1 and 5. These gears 28 may be rotated in any suitable manner by hand or by an electromotor. Meshing with the bevel gears 28 are bevel gears 30 corresponding in number 100 to the number of contacts of the fabric F with the cylinder 11. The gears 30 are carried by spindles 31 which are shiftable radially in bearings 32 formed on the side walls and bearings 33 formed by the shell of the casings 29. To allow 105 of a relative shifting motion between the gears 30 and their spindles 31 the former are splined on the latter as at 34, Fig. 5. The spindles 31 extend by their outer ends into hollow projections 35, which contain helical springs 36 tending to 110 force the spindles 31 inwardly towards the centres of the bevel gears 28. The spindles 31 have an intermediate screw threaded portion 37 engaging with an internally threaded opening 39 of yokes 38. Rigidly connected with the yokes 38 are parallel rods 40 which extend shiftable through openings of the shells of the casing 29 and have rigidly fastened to their outer ends yokes 41. Rotatably mounted in the opposite 115 ends of the yokes are the tension rollers 12 which 120 serve to force the fabric into contact with the circumferential surface of the cylinder 11. Arranged between each pair of adjacent yokes 41 are crossheads 42 which carry the guide rollers 13, by means of which the fabric can be disengaged from the cylinder 11. The crossheads 42 are connected with the yokes 41 by links 43. Besides, the crossheads 42 are guided by rods 44 extending radially through the shell of the casing 29. The described mechanism is arranged at 130 both head sides of the cylinder 11, but may be operated from one side.

Instead of imparting movement to the crossheads 42 through the links 43 from the yokes 41, the spindles 44 may be screw-threaded and actuated in a similar manner as the spindles 37. However, in this case the thread of the spindles 44 must have a pitch different from that of the spindles 37.

When the bevel gears 28 are rotated in one 140 direction, the yokes 41 with the tension rollers 12 and the crossheads 42 with the guide rollers 13 are moved inwardly, so that the fabric will be presented to the action of the cylinder 11, as indicated by full lines in Fig. 4. When the bevel 145 gears 28 are rotated in the opposite direction, the rollers 12 and 13 are pushed outwardly so that the fabric is disengaged from the cylinder 11, as indicated by dot-and-dash lines in Fig. 4. If the fabric in passing round the cylinder becomes 150

subjected to a strain exceeding a certain measure, the tension rollers 12 and the guide rollers 13 will be forced outwards against the action of the springs 36 to relieve the fabric of such strain, 5 while on the other hand these springs press the rollers 12 and 13 yieldably inwards. Instead of the springs 36, there may also be used rubber buffers or any other elastic elements. The displacement of the guide rollers 13 takes place on 10 radial lines $y-y$ and that of the tension rollers 12 on lines $z-z$ forming an acute angle with the lines $y-y$, see Fig. 4. The relative arrangement and displacement of the rollers 12, 13 is so that 15 the tension of the fabric and the length of fabric on the cylinder are always the same, both when the fabric is in and out of contact with the cylinder.

The tension rollers 12 belonging to one section of contact have always the same distance one 20 from the other in any of their various positions because they are carried by one and the same yoke 41. However, the distance between two successive guide rollers 13 is greater when they are in their outer position than when they are 25 in their inner position. This increase of distance is in part compensated for by the fact that, when the rollers are in their outer position the fabric extends between the tension rollers 12 of each 30 set of these rollers on a straight line, while it extends on an arc of a circle when the rollers are in their inner position. Yet, this compensation is not sufficient to avoid an increased tension of 35 the fabric and a drawing of the same round the cylinder when the rollers are shifted to their outermost position. Now, in order to obtain full compensation and to prevent additional strain, the 40 guide rollers 13 are displaced a shorter distance than the tension rollers 12, that is to say they lag behind the latter, so that the path taken by the fabric from one tension roller over the 45 adjacent guide roller to the next tension roller is shortened. When the rollers 12, 13 are moved inwardly to present the fabric to the cylinder 11, the guide rollers 13 are again displaced a shorter distance than the tension rollers 12 with the result that the length of fabric passing over all 50 tension and guide rollers and the tension of the fabric remain unchanged, see Fig. 4.

It will be understood that there may be used 55 a variety of mechanical means for effecting the displacement of the tension and guide rollers and that the invention is not limited in this respect to the mechanisms just described.

As already stated, it is preferable to provide 55 means for driving the guide rollers 13 positively. Fig. 6 illustrates such a positive drive for the said rollers. The drive comprises an endless chain 45, sprockets 46 and pinions 47, 48. The chain 45 may have motion imparted to it by a sprocket 49 fast on the shaft of the roller temple 18. The pinions 48 are fixed on the shafts of the guide rollers 13 and take part in the displacement of the latter when the fabric is brought into or out of engagement with the cylinder 11. The drive 60 may also have any other suitable construction and may be changed so that only some of the guide rollers 13 are positively rotated.

Supported by one of the side walls of frame 10 near the top of the machine is an electromotor 50 which is designed to drive the brushing cylinder 14, the felting cylinder 15, the clearer roller 16, the brushing roller 17, the roller temples 18 and 18', the conveying roller 19 and the winding rollers 25, 26 through the spur gears 51, 52, 53, 54, 55, 56, 57, 58, 59, 60, 61, 62, 63, 64, 65, 66, 67, 68,

69 and the bevel gears 70, 71, 72, 73, 74, 75, 76, 77, 78, 79, see Figs. 1, 3 and 7. 55 is the driving pinion for the brushing cylinder 14. 68 is the driving pinion for the felting cylinder 15 and is swingable with the same. Pinion 65 drives the clearer roller 16 and is swingable with the same. Pinion 66 drives the brushing roller 17 and is swingable with the same. 60 is the driving pinion for the roller temple 18' and 69 the driving pinion for the bevel gears 70, 71, 72, etc. The sleeking cylinder 11 is driven from the shaft of the brushing cylinder 14 through a sprocket drive 80, 81, 82.

Suitable mechanisms are provided for moving the adjustable rollers into and out of operative position. The adjustment of the tension and guide rollers 12, 13 with relation to the main cylinder may be carried out by the mechanisms shown in and described with reference to Fig. 5. The adjustment of the guide and tension rollers 20, 21 relatively to the brushing cylinder 14 is effected 90 by movable arms 83, which are adapted to be raised and lowered by screws 84 operated through bevel gears 85. Instead of this device, there may also be used for the adjustment of the rollers 20, 21 a mechanism similar to that shown in Fig. 5. Worm gearings 86, 86' and 86'' actuated by spindles 87, 87' and 87'' provided with hand wheels 88, 88' and 88'' serve to bring about the adjustments of the felting cylinder 15, clearer roller 16 and brushing roller 17, respectively, see Figs. 3 95 and 7.

While the invention has been described as applied to a sleeking machine, it is not limited to such machines, but may as well be wholly or partly used in connection with nap raising and other 100 fabric dressing machines, and more particularly in connection with the working cylinders thereof.

Having thus described my invention, what I claim as new and desire to secure by Letters-Patent is:—

1. In a fabric dressing machine, the combination with a working cylinder of a plurality of guide and tension rollers for the fabric distributed about the circumference of the cylinder and adapted to bring the fabric into and out of engagement with successive sections of the cylinder surface, adjustable supports for the said rollers, and resilient means arranged to act on the supports for forcing the rollers yieldingly towards the cylinder.

2. In a fabric dressing machine, the combination with a working cylinder of a plurality of guide and tension rollers for the fabric distributed about the cylinder parallelly thereof, adjustable supports for the tension rollers, and resilient means arranged to act on these supports for yieldingly pressing the tension rollers against the circumferential surface of the cylinder.

3. In a fabric dressing machine, the combination with a working cylinder of a plurality of guide and tension rollers for the fabric distributed about the cylinder parallelly thereof, adjustable supports for the said rollers, resilient means acting on the supports to force the rollers yieldingly towards the cylinder, and means for adjusting the supports to displace the guide rollers and the tension rollers relative to each other and towards and away from the cylinder simultaneously but by different lengths of strokes.

4. In a fabric dressing machine, the combination with a working cylinder of a plurality of guide and tension rollers for the fabric arranged parallelly of the cylinder in spaced relation about its circumference, adjustable supports for the guide and tension rollers, means for adjusting the supports to displace the guide rollers and the

tension rollers relatively to the cylinder by different lengths of strokes, guides for the supports of the guide rollers causing the guide rollers to move on radial lines with relation to the cylinder, and guides for the supports of the tension rollers causing the same to move on lines inclined inwardly towards the said radial lines.

5. In a fabric dressing machine, the combination with a working cylinder of a plurality of 10 guide and tension rollers for the fabric distributed about the cylinder parallelly thereof, adjustable supports for the said rollers, resilient means acting on the supports to force the rollers yieldingly towards the cylinder, and means for 15 positively rotating at least some of the said guide rollers.

6. In a fabric dressing machine, the combination with a working cylinder of a plurality of 20 guide and tension rollers for the fabric distributed about the cylinder parallelly thereof, adjustable supports for the said rollers, resilient means acting on the supports to force the rollers yieldingly towards the cylinder, means for adjusting the supports to displace the guide rollers 25 and the tension rollers towards and away from the cylinders by different lengths of strokes, and means for positively rotating at least some of the said guide rollers.

7. In a fabric dressing machine, the combination with a working cylinder of a plurality of 30 guide and tension rollers for the fabric distributed about the cylinder parallelly thereof, adjustable supports for the tension rollers, means for adjusting the supports of the tension rollers 35 to displace the latter relatively to the cylinder, adjustable supports for the guide rollers, members interdependently connecting the supports of the tension rollers with those of the guide rollers and designed to transmit the movement of the 40 former to the latter.

8. In a fabric dressing machine, in combination with a framework, a working cylinder rotatably mounted in the side walls of the frame, guide and tension rollers for the fabric distributed about 45 the cylinder parallelly thereof, supports for the said rollers adjustable on the side walls of the frame substantially radially to the axis of the cylinder, rotatable central gears on the frame walls in line with the axis of the cylinder, and connecting rods between the central gears and the roller supports adapted to transmit motion 50 from the gears to the supports to shift the same radially in one direction and the other for displacing the rollers relatively to the circumference of the working cylinder.

55. 9. In a fabric dressing machine, in combina-

tion a framework, a working cylinder rotatably mounted in the side walls of the frame, guide and tension rollers for the fabric distributed about the cylinder parallelly thereof, supports for the said rollers adjustable on the side walls 80 of the frame substantially radially to the axis of the cylinder, resilient means acting on the supports for forcing the rollers yieldingly towards the cylinder, rotatable central gears on the frame walls in line with the axis of the cylinder, and connecting rods between the central gears and the roller supports adapted to transmit motion 85 from the gears to the supports to shift the same radially in one direction and the other for displacing the rollers relatively to the circumference of the working cylinder.

10. In a fabric dressing machine, in combination with a framework, a working cylinder rotatably mounted in the side walls of the frame, guide and tension rollers for the fabric distributed 90 about the cylinder parallelly thereof, supports for the said rollers adjustable on the side walls of the frame substantially radially to the axis of the cylinder, resilient means acting on the supports for forcing the rollers yieldingly towards the cylinder, rotatable central gears on the frame walls in line with the axis of the cylinder, connecting rods between the central gears and the roller supports adapted to transmit motion from 95 the gears to the supports to shift the same radially in one direction and the other for displacing the rollers relatively to the circumference of the working cylinder, and means for positively driving at least some of the said guide rollers.

11. A sleeking machine for textile fabrics, comprising a frame, a sleeking cylinder in the lower portion of the frame, a brushing cylinder and a felting cylinder in the upper portion of the frame, means for conveying the fabric successively to and around the said cylinders, these means including a plurality of guide and tension rollers for the fabric distributed around the sleeking and brushing cylinders, adjustable supports for these guide and tension rollers, means for adjusting the supports to displace the guide rollers 110 and the tension rollers towards and away from the cylinders by different lengths of strokes so as to keep the length and tension of the fabric unchanged both when it is in and out of engagement with the cylinders, motor-driven gearings 115 for imparting positive rotation to the working cylinders and conveying rollers, and a vat for the reception of the fabric underneath the sleeking cylinder.

AUGUST SCHIFFERS. 130
